SHIELD ATTACHABLE TO A HELMET

Willis C. Fortson, Mableton, Ga.
(2651 Veracruz Court, Morrow, Ga. 30260)

Filed May 23, 1974, Ser. No. 472,548

Term of patent 14 years

Int. Cl. D2—03

U.S. Cl. D2—233

FIG 1

FIG 2

FIG 3

FIG 4

FIG 5**FIG 6****FIG 7****FIG 8**

FIG. 1 is a front perspective view of a shield attachable to a helmet showing my new design;

FIG. 2 is a side elevational view thereof;

FIG. 3 is a front elevational view;

FIG. 4 is an elevational view of the side opposite that shown in FIG. 2;

FIG. 5 is a rear elevational view;

FIG. 6 is a top plan view;

FIG. 7 is an outside plan view in an unfastened extended flat position; and

FIG. 8 is an inside plan view thereof.

I claim:

The ornamental design for a shield attachable to a helmet, substantially as shown.
